185,681

VELOCIPEDE FRONT FENDER AND TRUSS ROD ENSEMBLE

Viktor Schreckengost, Cleveland Heights, Ohio, assignor
to The Murray Ohio Manufacturing Company, Nash-
ville, Tenn., a corporation of Ohio

Application March 5, 1959, Serial No. 54,855

Term of patent 14 years

(Cl. D34—15)

FIG. 1

FIG. 2

FIG. 3

FIG. 4

FIG. 5

Fig. 1 is a perspective view of a tricycle, the general structure of which is indicated in dashed outline, and in solid lines showing my new design;

Fig. 2 is a left side elevational view corresponding to Fig. 1;

Fig. 3 is a plan view of the front fender and truss rod appearing in Figs. 1 and 2;

Fig. 4 is a front elevational view of Fig. 3; and

Fig. 5 is a rear elevation view of Fig. 3.

I claim:

The ornamental design for a velocipede front fender and truss rod ensemble, substantially as shown and described.
